H. BEHM.
COMBINED VIBRATOR AND SPRAY.
APPLICATION FILED AUG. 15, 1914.

Patented May 15, 1917.

UNITED STATES PATENT OFFICE.

HENRY BEHM, OF ELIZABETH, NEW JERSEY, ASSIGNOR TO WILLIAM S. HEAL, OF ELIZABETH, NEW JERSEY.

COMBINED VIBRATOR AND SPRAY.

1,225,752.

Specification of Letters Patent. Patented May 15, 1917.

Application filed August 15, 1914. Serial No. 856,886.

To all whom it may concern:

Be it known that I, HENRY BEHM, a subject of the Emperor of Germany, and a resident of Elizabeth, county of Union, and 5 State of New Jersey, have invented certain new and useful Improvements in Combined Vibrators and Sprays, of which the following is a specification.

This invention relates to an improved 10 vibrator which is adapted to be operated by a current of fluid, either water, air or the like, which is preferably conducted to the vibrating part of the vibrator by flexible means, such as a hose, so as to permit 15 the portable use of the vibrator.

The vibrator consists of a holder which has vibrating elements which are adapted 20 to be placed against the body, the holder having, mounted therein, a rotor which is unbalanced so that when it revolves the centrifugal force of the rotor causes a vibration of the holder.

The invention further consists in providing such a holder with a rotor and a 25 nozzle for projecting the fluid against the rotor, the nozzle and the rotor being adapted to be placed into and also out of alignment so that the stream of fluid can be used direct without vibration of the holder, but 30 also used so as to allow vibration of the holder when the rotor is in the path of the stream from the nozzle.

The invention comprises further a rotor 35 that is suspended so that it can be moved at will from the path of the stream from the nozzle and held in this latter position until it is desired to again cause the rotation of the rotor. The invention also provides a handle which can be attached to the 40 holder in such a manner as to permit the handle to be placed in different positions and held in these different positions.

Another object of the invention is to provide a means for attaching the handle to the holder, said attaching means also acting to clamp the hose to the back of the holder, thus insuring a tight joint and preventing leaks.

The invention is illustrated in the accompanying drawing, in which Figure 1 is a view showing the holder portion in section with the handle and flexible hose in elevation. Fig. 2 is a section on line 2, 2, in Fig. 1. Fig. 3 is a section through the 55 handle attaching device taken on line 3, 3,

in Fig. 1. Fig. 4 is an elevation, broken away, of a modified form of construction. Fig. 5 is an elevation broken away on one side, this view illustrating another modified form of construction.

The vibrator comprises a holder 10 of any desired form, the preferred shape being cup-shaped, open at the front and having, at the back, a small, projecting mouth 11 which is provided on its inner end with a 60 nozzle 12, the nozzle being placed inside the holder and projecting a stream of fluid toward the open end of the holder. A flexible hose 13 is usually used with the vibrator and has its end 14 placed around the mouth 11 of the holder. A collar 15 is placed over the end 14 of the hose, the collar having wings 16. Against one of the wings is arranged a plate 17 of a handle 18, the plate and the wings having a bolt or 65 screw 19 passing through them with suitable nuts 20 for fastening them together and drawing the wings toward each other so as to clamp the hose tightly around the mouth 11. The plate 17 is adapted to swing 70 on the stud or screw 19 and can be swung to different positions, as desired. To lock the handle in certain desired positions, locking means or holding means are devised for securing the handle in place. One form of 75 holding the handle is illustrated in the drawing in which the plate is provided with a projection 21 which is adapted to rest in recesses 22, the spring of the metal, of which the wings and the plate are composed, allowing 80 for the binding action which is sufficient to hold the handle in the desired position. The recesses 22 are provided in suitable 85 number, according to how many positions the handle is to be fixed in.

The open face of the holder is provided 90 with vibrating elements which can be of any type and which can be secured in any manner. The form shown in Figs. 1 and 2 comprises a ring 23 made of elastic material 95 so that it can be bent over the bead 24 at the open end of the holder, the ring 23 having posts or fingers 25, these being usually made of rubber and providing a series 100 of vibrating elements which can be placed against the skin without danger of abrasion. I prefer to fasten the screen 26 against the open face of the holder, this screen being held by the ring 23 or in any other way, 105 the screen acting to transform any stream 110

of fluid from the nozzle, that hits the screen, into a spray. It will be understood that any suitable perforated sheet on the open face of the holder, which sheet would act similar to a screen in dividing the stream, can be used. An axle 27 is arranged across the holder and acts to support a rotor 28, the rotor having paddles or wings 29, these paddles being adapted to receive 10 the stream from the nozzle 12, whereby the rotor is rotated.

To magnify or to make more positive the vibrating motion, the rotor is usually unbalanced, that is, one side is heavier than the other, and in the form shown this is accomplished by making the hub 30 eccentric so that when it rotates the centrifugal force causes a swinging or vibration of the rotor sufficient to make a positive vibrating action 20 of the holder, and particularly of the vibrating elements 25. In the form of device shown in Figs. 1 and 2, the rotor is arranged to slide on the axle 27, the sliding being limited by flanges 31 on the axle 27. It will thus be seen that when the vibrator is held 25 in a position to cause the rotor to be affected by gravity and slide down against one of the flanges, the rotor will be in the path of the stream coming from the nozzle 12, and the device can be used as a vibrator and the stream of fluid then passes on to the screen 30 26 and passes from the holder. If the device is to be used as a spray alone the holder is tilted and the rotor slides to the position 35 shown in dotted outline at *a* in Fig. 2, and is not rotated in this position, since the stream of fluid passes directly onto the screen and from that it emerges from the holder as a spray, being broken up by the screen.

To insure the absence of leaks on the sides of the holder, and to also provide stiffness to the structure, I prefer to provide the axle 27 with heads 32, as will be evident from 40 Fig. 2.

In Fig. 4 I show a modified form in which the rotor 28 is mounted on the axle 27 and is held in one position, the illustration showing flanges 33 to hold the rotor in place 50 against sliding on the shaft. In order to use the device as a spray without vibration, the form shown in Fig. 4 covers a structure embodying a movable nozzle 34 which is mounted on a plate 35 which slides in ways 55 36 on the back of the holder 10. The hose 13 is connected in any way to the mouth 37 of the nozzle. A finger-piece 38 is suitably disposed so that the nozzle can be shifted as desired so as to cause the stream from the 60 nozzle to be directed against the rotor or to pass by the rotor without engaging it. In Fig. 4 I also show a modified form of vibrat- 65 ing element which consists of a ring 38a

which is of any suitable material, although rubber is preferred, the ring having an annular, thin projecting web 39a which is adapted to vibrate when held against the skin of the user and the rotor is in the path of the stream issuing from the nozzle.

In Fig. 5 is still another modified form, 70 the rotor 28 being provided, in this type, with a collar 39 that is grooved as at 40, and a stem 41 projects through the side of the holder 10 and has its end 42 in engagement with the slot 40 whereby the rotor 28 can 75 be shifted by sliding the stem 41 in or out of the casing. A handle 43 is provided for the operation of the stem, and suitable latches 44 are provided for securing the rotor in fixed positions when it is desired to 80 lock the rotor against accidental movement from the position in which it is desired to hold it.

The vibrator herein shown is adapted for use in different ways and can be easily and 85 quickly changed from a spray or shower to a combined spray and vibrator.

I do not wish to be understood as limiting myself to the exact form of apparatus shown, as changes can be made in the construction of the parts and also in their disposition without departing from the scope of the invention.

Having thus described my invention, what I claim is:—

1. A vibrator comprising a holder, a nozzle for injecting fluid into the holder and out through the front, a rotor arranged to rotate in the holder, and means for suspending the rotor so that it can be shifted into and out of the path of the stream of fluid.

2. A vibrator comprising a holder, a nozzle for directing a stream of fluid through the holder, a perforated screen in the holder and opposite the nozzle to transform the stream into a spray, and an unbalanced rotor mounted between the nozzle and the screen and adapted to impart a vibration to the holder by its rotation.

3. A vibrator comprising a holder, a nozzle for directing a stream of fluid through the holder, a perforated screen in the holder and opposite the nozzle to transform the stream into a spray, a rotor rotatably arranged in the holder, and means for suspending the rotor so that it can be moved into and out of the path of the stream of fluid from the nozzle.

In testimony that I claim the foregoing, I have hereto set my hand, this 13th day of August, 1914.

HENRY BEHM.
